INSTANT ACTION BOAT BAILER

Gordon S. Baldwin, Fort Frances, Ontario, Canada

Application July 30, 1957, Serial No. 675,102

5 Claims. (Cl. 114—185)

The present invention relates to improvements in means for removing water from boats and more particularly to the provision of a bailer in the underside of a boat through which water is automatically drained when the boat is in motion.

General objects of this invention are to provide an automatic bailer which may easily and quickly be installed in a boat and which, at the same time, embodies a simple, practical construction which will be rugged and durable in use, and which may be manufactured and assembled with comparative economy.

With these and other objects in view, the invention consists in certain novel features of construction and combination and arrangement of parts as will be more fully hereinafter set forth and pointed out in the claims, reference being had to the accompanying drawings forming a part hereof, wherein like numbers refer to like parts.

In the drawings:

Figure 1 is a sectional view of the new boat bailer taken along lines 1—1 of Figure 3;

Figure 2 is a sectional view of a boat bailer attached to a fragmentary section of the boat with parts of the boat bailer removed;

Figure 3 is a top plan view of the new boat bailer;

Figure 4 is a top plan view of the evacuator plate;

Figure 5 is a top plan view of means remotely controlling the new boat bailer; and,

Figure 6 is a side view of the remote device for controlling the boat bailer with a portion of the boat bailer shown in broken lines.

The common practice in the installation of boat bailers of the self-bailing type is to bore or drill a hole in the underside or bottom of the hull of the boat. This hole is usually located near the center line and as near the stern as possible. This hole, while it may vary slightly in size, for general description could be stated to be three-quarters of an inch in diameter.

The objective is to provide means of readily opening this hole when it becomes desirable or necessary to remove water, technically known as "bilge water," from the boat and to provide a means of quickly closing this hole when the water has been drained.

Forward speed of five miles per hour or more is required to draw the bilge water from the boat out through the boat bailer.

The instant action boat bailer consists of a drawn brass or the like valve housing with three feet-like plates drilled for attaching the housing permanently to the inside of the hull and directly on center over an opening.

The mechanism is activated by the valve lifting handle which is attached by means of a locking pin to a valve lifting stem. The valve lifting stem is inserted through a neoprene or like material valve plug with a pressure valve activating spring placed between the inside of the valve housing and the valve plug.

To place the instant action boat bailer in action, the valve lifting handle is raised to the vertical position and, being an eccentric, it in turn raises the valve plug to the

open position. When the valve plug is in the open position and with the boat travelling forward at a speed of, or in excess of, five miles per hour, the bilge water will be drawn out of the hull through the bailer.

5 To close the instant action boat bailer through which the bilge water has been drawn out of the boat, the valve handle is simply flicked down, that is, to the original horizontal position, and the pressure spring automatically closes and seats the valve plug into the opening in the hull, stopping the flow of water either way.

Referring to the drawings in detail, the numeral 10 is used to designate the bottom of a boat having an opening 20 therein and having valve seat 14 suitably secured to the boat about the opening 20. On the outside of the 15 boat is secured evacuator plate 12 having sloping channel 40 therein. The channel 40 is preferably in the form of an arc of a circle. The valve seat 14 is provided with openings which will cooperate with the openings 42 in the evacuator plate 12 in securing the feet 18, valve seat 14 and 20 evacuator plate 12, in place separately; that is, the plate 12 to the boat, the valve seat 14 to the boat, and the feet 18 to the valve seat ring.

The housing 16 is threaded for reception of removable top 34 and openings 15 are provided between legs of the 25 housing 16. The legs are bent at substantially right angles to the legs to provide feet 18. Valve stem 26 passes through valve plug 22 and top 34. Positioned between valve plug 22 and top 34 is spring 24 which normally urges the valve plug outwardly from the housing 30 16. The upper end of valve stem 26 is drilled to provide opening 28 through which lock pin 30 extends in securing valve handle 32. The valve handle includes substantially bifurcated circular portion generally indicated at 38, flat nose portions 31 which provide space 33. The handle 35 32 is secured off center of the portion 38.

To place the bailer in operating position the handle 32 is raised until the portions 31 rest upon the top 34. The raising of the handle raises the valve plug 22 against the spring 24 placing the interior of the boat in communication 40 to the outside of the boat through openings 15 between legs extending from body 16, opening 20 in boat, and channel 40. When the valve plug is in the open position just described with the boat travelling at the proper rate of speed, the bilge water is drawn out of the hull 45 through the bailer.

On movement of the valve handle downwardly the pressure spring 24 automatically seats the valve plug on the valve seat 14 closing hole 20 in the hull.

The diameter of valve plug 22 is greater than the diameter of the hole 20. The nose of valve plug 22 extends into hole 20 when in the closed position. The valve plug may be made of suitable material such as neoprene or the like.

The valve stem 26 being eccentrically attached to portion 38 of handle 32 requires only a light touch to cause the release thereof. This action makes it easy to use remote control for opening and closing of the bailer. In Figure 5 is an arrangement that permits remote control. Encircling band 46 is secured around body 16 by means

60 of adjustable member 48. Pivotally attached to band 46 at 58 is bail 50. Attached to bail 50 and extending from one of the pivots 58 is arm 52. Secured to arm 52 and extending, for example, to the forward part of the boat is cable 54. Valve lifting handle 32 of the bailer 65 extends through member 56 or rests in a slot therein.

The arrangement of part of the bailer in the manner shown insures that the bailer will not foul with sand, dirt, or other materials in the bilge water. By way of example a cylindrical member, such as brass tubing, in a length 70 of about 2½ inches long has three sections removed to provide legs about 1 inch in length. The three legs are bent at their free end to form feet by which the bailer is

secured to the boat. Between the legs are openings through which the bilge water flows when being removed from the boat. The valve body should extend substantially perpendicular to the boat bottom.

What is claimed:

1. An automatic bailer for boats, a vertical extending cylindrical housing having a closed end and spaced legs on the other end, each of the legs of the cylinder bent at substantially right angles to provide securing means for fastening the housing to the boat bottom, a valve plug in the housing, a valve stem extending through the valve plug and the closed top, a spring positioned around the valve stem and between the top and the valve plug, a partially bifurcated substantially circular member secured to the said valve stem at a point offset from the center portion of the circular portion, and a part of the bifurcated portion being flat and adapted to rest on the closed end of the cylindrical housing when the valve plug is raised against the spring.

2. An automatic bail for a boat comprising a boat having a bottom, a plate having an opening therein positioned on opposite sides of the boat bottom, a cylindrical housing having feet extending at an angle thereto, means extending through the feet and two plates for securing them in operating position, a valve plug mounted in the cylindrical housing, a removable cover closing an end of the housing, a valve stem extending through the valve plug and the said cover, a spring mounted between the said cover and said valve plug, and an eccentrically attached valve handle secured to the valve stem, said valve handle having a substantially flat portion adapted to rest upon said removable cover when the spring is compressed.

3. An automatic boat bailer, a boat having a bottom, a valve seat secured to the boat bottom about an opening in the said boat bottom, a cylindrical housing having a closed end and legs extending from the other end, said legs bent at an angle at the ends to provide feet for securing the housing to the boat, a valve plug slidably mounted in the housing, a valve stem extending through the valve plug and the closed end of the housing, a spring positioned between the closed end of said housing and the valve plug, and a valve handle eccentrically connected to the valve stem, said valve handle having a substantially

flat nose portion which rests upon the closed end of the housing when the spring is compressed between the valve plug and closed end of housing.

4. A device of the class described in combination with a boat having a bottom with an opening therein, an evacuator plate secured to the boat bottom adjacent the opening therein, an arc-shaped channel in the said plate, a valve seat secured about the opening in the boat and on the opposite side from the evacuator plate, a cylindrical housing having a closed end and spaced legs on the other end, the legs bent to provide feet, securing means for fastening the housing, valve seat and evacuator plate in operating position, a valve plug mounted in the housing, a valve stem extending through the valve plug and the closed end, and a bifurcated handle eccentrically attached to the said valve stem, said handle having a substantially flat end offset from the point of attachment of the handle to the valve stem.

5. An automatic boat bailer comprising a substantially vertical casing having a closed end and spaced legs on the other end, the legs bent at substantially 90° to provide feet, a valve seat upon which said feet rest, an evacuator plate secured in spaced relation to the valve seat, an arc-shaped channel in said plate, securing means passing through the legs, valve seat and evacuator plate, a valve plug mounted in the casing, a valve stem extending through the valve plug and the closed end of the casing, a bifurcated valve handle having a cam portion eccentrically attached to the said valve stem, the cam portion of the valve handle having a substantially flat portion offset from the point of attachment of the handle to the valve stem, and a spring means between the closed end of the casing and the valve plug.
